UNITED STATES PATENT OFFICE.

JOHANN G. PETERSON, OF JERSEY CITY, NEW JERSEY.

ELECTRICAL ATTACHMENT-PLUG.

1,313,328.

Specification of Letters Patent.

Patented Aug. 19, 1919.

Application filed December 1, 1917. Serial No. 204,961.

To all whom it may concern:

Be it known that I, JOHANN G. PETERSON, a citizen of the United States, residing at Jersey City, in the county of Hudson and 5 State of New Jersey, have invented certain new and useful Improvements in Electrical Attachment-Plugs, of which the following is a specification.

This invention relates to an electrical attachment plug. Although it is of primary importance when used in conjunction with what is known as an extension connection, it may be used in whole or in part in other ways. I have several objects in view; 10 among these is the provision of an article which is susceptible of inexpensive manufacture, quite compact yet in which when occasion is required adequate space is afforded for bringing together within the plug, the 15 wires. The appliance comprises other features of novelty and advantage, which with the foregoing will be stated at length in the following description, wherein I will outline in detail that form of embodiment of the invention which I have selected for illustration in the drawings accompanying and forming part of the present specification. Obviously I do not restrict myself to this 20 particular disclosure; I may depart therefrom in several respects within the scope of the invention defined by the claims following said description.

Referring to said drawings:

Figure 1 is a longitudinal section of a 35 plug involving the invention.

Fig. 2 is a bottom plan view of the same.

Fig. 3 is a horizontal section on the line 3—3 of Fig. 1, looking in the direction of the arrows.

40 Fig. 4 is a detail in longitudinal section on the line 4—4 of Fig. 1, looking in the direction of the arrow.

Like characters refer to like parts throughout the several views, which are on 45 different scales.

The appliance involves in its structure a multi-part body. As shown this body comprises the sections 2 and 3 which are of some insulating material such as a moldable composition. They are in the main of cylindrical form and are separated or spaced apart to present a chamber or cavity 4 surrounded by the shell 5. It is to be noted that the shell 5 and certain of its adjuncts turn on the 55 body sections 2 and 3. These body sections are mechanically connected together, as I

will hereinafter explain. The shell 5, however, is freely turnable on the body of the plug made up in the present case of these two sections.

The upper body section 2 may as shown have molded therein the terminals 6 and 7 of suitable conducting material, the inner ends of these terminals 6 and 7 being expanded as at 8 which presents a convenient 60 way of properly fixedly uniting the terminals 6 and 7 with the body section 3. The latter has an opening 9 through it for the passage of the wires 10 and 11, the free ends of these wires being skinned or bared and 65 being electrically connected with the two terminals 6 and 7. I have shown tapped through these terminals the coaxial screws 12, the heads of which face outward and are on the outer sides of the terminals. Around 70 the shanks of the screws on the outer sides of the two terminals, the bared ends of the two wires 10 and 11 will be wrapped or coiled one or more times and the screws being fed inward, the wires will be forced 75 against the terminals to secure a proper connection. I might explain that this mechanical and electrical connection is made while the parts of the plug are separated, and I will also hereinafter set forth how this latter 80 function is attained.

The body section 2 has molded therein the ring 13 from which projects inwardly the arm or post 14. This ring 13 and its projecting arm or post can be stamped from 85 sheet metal and plays a part in the conduct of the current. Its periphery is flush with the periphery of the body section 2 yet the post or arm 14 is surrounded by the material of said body section in which material the arm is naturally embedded so as to properly anchor the same. This arm or post and a companion arm or post as 15 constitute in effect terminals. The arms 14 and 15 are in parallelism longitudinally of 90 the plug, the arm 15 having an inwardly extending base 16, set in a channel 17 on the inner side of the body section 2, the sides of the channel naturally preventing side movement of the base 16. This channel intersects the perforation 18 through which the screw 19 extends, the head of the screw 95 extending through a registering perforation in the base 16 and holding the base firmly and solidly in the channel.

100 The threaded end of the screw 19 is connected with the central end contact 20 fit-

ted against the truncated end of the body section 2 and having circumferential lugs 21 diametrically opposite each other as shown which are embedded in the material of the body section 2 to thus insure the holding in position under all conditions of the central end contact. As will be clear this central end contact is centrally intersected by the longitudinal axis of the plug which coincides with the longitudinal axis of the screw 19. The posts or arms 14 and 15 have longitudinal slots 22 open at the free ends of the arms or posts and which are intended for the passage of screws 23 threaded into the contacts 6 and 7, the heads of the two screws bearing against the posts 14 and 15 to press the same when the parts are in the assembled relation against the terminals 6 and 7. By backing out these two screws the posts or arms 14 and 15 are unclamped from the terminals 6 and 7, in view of which circumstance if other conditions permit, the body sections 2 and 3 can be longitudinally separated. The shell 5 has at the lower end the inturned flange 24 which has a bearing upon the ring 13 and turns on said ring.

Surrounding the shell 5 which after the customary fashion may be externally threaded to fit the Edison incandescent lamp socket, is the band or ring 25 of insulating material such as composition. This ring 25 fits against the fillet 26 on the shell and is in turn abutted by the ring 27 also of insulating material and into which the peripheral upper portion of the shell 5 is expanded. The upper portion of the shell 5 is, therefore, protected, so that it can be run into a socket sufficiently to make electrical connection with the main or supply without possibility of injury to the manipulator.

The shell 5 has between its ends an opening 28, and the primary purpose of this opening is to reach the heads of the screws 23, so that said screws can be backed out to free the arms 14 and 15 from the contacts 6 and 7, so that the body sections 2 and 3 can be separated. When they are thus separated the wires 10 and 11 will be mechanically and electrically connected with the terminals 6 and 7 as already set forth after which the body sections 2 and 3 will be mechanically connected.

What I claim is:

1. An electrical attachment plug comprising an insulating body in sections distinct and spaced from each other, a contact shell around both sections of the body, terminals extending from one of the sections of the body, said section to which said terminals are connected, having means for the passage of wires, arms separably connected with said terminals inside the shell, one of said arms being electrically connected with said contact shell, said terminals and arms constituting the sole means for mechanically connecting said insulating sections, a central end contact on the other section of the body electrically connected with the other arm, and means for electrically connecting the wires with said terminals.

2. An electrical attachment plug comprising an insulating body in sections distinct and spaced from each other, a contact shell around both sections of the body, terminals extending from one of the sections of the body, said section to which said terminals are connected, having means for the passage of wires, arms separably connected with said terminals, inside the shell, one of the arms being electrically connected with said contact shell, and a screw extending through the other of the arms and the other insulating section, and a central end contact fitted against said other insulating section and having circumferential means embedded therein and to which said screw is connected.

3. An electrical attachment plug comprising an insulating body having a first section and a second section distinct and spaced from each other, a contact shell around both sections of the body, terminals extending from the first section of the body, said first section having means for the passage of wires, a ring molded in the second section of the body and provided with an arm separably connected with one of said terminals, said ring being also electrically connected with said shell, a second arm separably connected with the other terminal, a central end contact on the second section of the body electrically connected with said second arm, and means for electrically connecting wires with said terminals.

4. An electrical attachment plug comprising an insulating body having a first section and a second section, a contact shell around both sections of the body, terminals molded into the first section of the body and inclosed by the shell, an arm having a molded connection with the second section of the body and electrically connected with said shell, said arm being detachably connected with one of said terminals, a second arm detachably connected with the other terminal, said arms also being inclosed by the shell, a central end contact on the second section of the body electrically connected with said second arm, and means for connecting wires with said terminals.

5. An electrical attachment plug comprising an insulating body having a first section and a second section distinct and spaced from each other, the first section having an opening for the passage of wires, terminals molded in said first section, a contact shell swiveled around both sections of the body, a ring molded in the second section of the body and provided with an arm having an open slot, a screw extending through the open slot and tapped into one of said ter-

- minals, a second arm also having an open slot, a screw extending through the open slot of the second arm and threaded into the other terminal, said second arm being 5 provided with a base, a screw extending through said base and also through the second section of the body, and a central end contact fitted against the second section of the body and threaded to receive said last mentioned screw, the central end contact being provided with circumferential lugs pressed into the stock of the second section of the body, and means for electrically connecting wires with the said terminals.
- 15 6. An electrical attachment plug comprising an insulating body in sections distinct and spaced from each other, a contact shell around both sections of the body, terminals extending from one of the sections of the body, said section to which said terminals 20 are connected, having means for the passage of wires, arms separably connected with said terminal inside the shell, one of said arms being electrically connected with said contact shell, said terminals and arms constituting 25 the sole means for mechanically connecting said insulating sections, a central end contact on the other section of the body, electrically connected with the other arm, the central end contact having means embedded 30 in said body, and means for electrically connecting the wires with said terminals.
- In testimony whereof I affix my signature in the presence of two witnesses.

JOHANN G. PETERSON.
